UNITED STATES PATENT OFFICE

2,372,141

MACHINE TOOL TABLE STOP

John M. Walter, Cincinnati, Ohio, assignor to
The G. A. Gray Company, Cincinnati, Ohio, a
corporation of Ohio

Application May 25, 1943, Serial No. 488,368

9 Claims. (Cl. 90—58)

In machine tools having traveling tables, such for example as metal planers, the tables on occasion are not stopped at the end of a traverse thereof, and continue by inertia to move beyond the supporting bed on which they are mounted and guided. Thus if a direct connected motor drive fails to stop, and the large gear wheel or bull wheel of a planer continues to rotate, the table may continue to move, with the rack out of mesh with the bull wheel, and entirely out of control of the operator.

In large planers where the table is very heavy, and runs away or coasts on its support, great danger may arise. The tables may coast as far as 25 feet beyond the normal limit of movement, and with higher platen speeds such as are being developed at present, even greater movement can be expected.

Present table speeds run to 240 feet per minute, and the tables will exceed fifty tons in weight. The force with which they move by inertia at the end of a stroke is in proportion directly to their mass and as the square of their speed. Thus an escaped table may run into the wall of a building and demolish it. It may strike a workman and kill him. It may crush adjacent pieces of machinery, and incidentally mar or ruin the work being operated upon.

Particularly in large planers, stopping devices have been applied to eliminate the danger now noted; but these are heavy and expensive. For example, as emergency stops of a planer table weighing 55 tons, with a maximum speed of only 110 feet per minute, there were required four spring stops, two for each corner of the table, said stops supplied with springs forty-three inches long and made of one and one-quarter inch spring steel, calculated to support a load of 14,000 pounds each. On the same calculations, for a like table having a maximum speed of 240 feet per minute, the springs would have to be built to take a load of 65,000 pounds each.

It is the object of my invention to provide a very simple and inexpensive stop, of little bulk, and highly effective. To this end I provide on the table and on the bed which supports it respective elements in the form of a block or blocks which are to be cut, and tools which are to cut into the blocks. In other words, if the table runs out of mesh with the drive, a force will be applied to stop the table, arising from the reactance of tools cutting into the blocks. This occurs without undue impact.

The effectiveness of this mode of supplying a

stop can be appreciated when I note that in a test, using my stopping devices, a table of 42 tons in weight, running at 240 feet per minute as it came out of driving mesh with the bull wheel, was stopped in nine inches.

Various modes of mounting the tools and mounting the blocks may be provided and it makes no difference whether the tool mounting is on the table or the bed, providing that the blocks into which the tools cut are mounted on the other of the two members. Or the arrangement could be alternative, one cutting tool arrangement at one side of the bed to engage a block on the table, and a block on the other side of the bed to engage a tool on the table. Again, a self-contained block and tool combination may be provided, normally free of one of the members, but interposed for example as a stop in the path of the table, or of one or more lugs beneath the table. Tools can be mounted on the table so as to cut directly on the bed, or on a block-like protruberance integrally formed on the bed, or tools mounted on the bed can be positioned to cut the table casting; but the convenience of providing renewable blocks to be cut will be evident. Moreover the blocks may be so designed as to be capable of repositioning so that each block may be used to present a plurality of fresh cutting surfaces.

Ordinarily for a large planer there will be a cutting tool and cutting block arrangement for each of the four corners. Tools may be arranged in a gang of several tools, so as to take too much load from a single tool, and indeed various modifications may be desirable, depending upon the structure of the machine and the convenience in arranging the emergency stopping devices.

In the drawings I have shown several modifications, without intent however to limit the possible variations, for the purpose of explaining my invention by several examples, the novelty thereof being set forth in the appended claims.

In the drawings:

Figure 1 is a plan view of a planer table and bed, showing the stopping device mounted altogether on the bed, but arranged to be picked up by lugs located on the underside of the platen or table.

Figure 2 is a side elevational detail showing the table, lug and stopping device.

Figure 3 is a section on the line 3—3 of Figure 5.

Figure 4 is a section on the line 4—4 of Figure 3.

Figure 5 is a section on the line 5—5 of Figure 3, the group of figures showing the arrange-

ment for mounting the stopping device entirely on the bed, the relation of the table thereto being one of abutment, if it runs beyond the driving means.

Figure 6 is a plan view illustrating a structure in which the cutting tools are mounted on the underside of the table, and the blocks to be cut are on the bed.

Figure 7 is a detail cross section showing the tool holder, cutting tool and block against which the cutting is performed at one end of the machine.

Figure 8 is a like view showing the arrangement on the opposite end of the machine.

Figure 9 is a plan view of a planer table and bed showing yet another arrangement of tools and blocks.

Figure 10 is a side elevation thereof.

Figure 11 is a partial end elevation thereon on an enlarged scale.

Figure 12 is a partial side elevation thereof.

Referring to the first modification, shown generally in Figures 1 and 2 and detailed in Figures 3 to 5 inclusive, a structure is indicated which is recommended in instances where it is not convenient to get at the underside of the table, but where the bed has spaces for the mounting of the stopping devices. The table is indicated at 1 and the bed at 2. There are two abutment lugs provided on the underside of the table as at 6 and 7, one for coating with the stopping device at each end of the stroke or traverse of the table. There will be generally similar stopping devices at each end of the bed, one in alignment with each lug. A stopping device is indicated generally at 8 in Figures 1 and 2.

As detailed in Figures 3, 4 and 5 each stopping device consists of a pair of parallel spaced metal blocks 9, 9. Guide blocks 10, 10 are located above them, and are shaped to provide a channel in which a tool holding slide 11 is slidably mounted. The spaced blocks and the guide blocks are bolted to the bed 2 as shown.

The slide 11 has mounting means to hold a pair of tools 13 and 14, one on each side, the tools being arranged to cut into the blocks 9 at their inner faces. The slide 11 may be perforated or recessed to receive the tools, which can be held in place by means of set screws 15 and 16. A protuberance or abutment 12 on the underside of the slide acts as a backstop for the tools. It may be noted that the blocks 9 can be initially cut away or relieved as at 9a so that the slide 11 can lie within the length of the guides 10. A loose sheet metal cover may be placed over the assembly to protect it from the accumulation of foreign material.

As has been indicated, the slide 11 is so located that, should the table escape from its drive and start running loose, the lug 7 will strike the slide and move it toward the end of the bed. This causes the tools to cut into the two parallel blocks 9, and dissipates the kinetic energy in the escaped table in the cutting operation. The result is to stop the escaped table in a very short space and with relatively little jarring.

In Figure 6 a pair of blocks 17 are bolted to the bed at one end while at the other end there are fastened another pair of blocks 18 more widely spaced. The latter blocks may be bolted to the side rails of the bed as indicated in Figure 7. While slightly different arrangements of tools and blocks have been shown at either end of the table and bed (and as detailed in Figures 7 and

8), the arrangement at both ends may be identical.

Near one end of the table, and beneath it, tools are fastened as at 20 in Figure 6, the tools being so spaced that each of them will cut one of the blocks 17 if the table 1 moves far enough to the right in Figure 6. Another pair of tools is mounted at the position indicated at 21 in Figure 6 so that these tools can cut the blocks 18 if the table 10 moves far enough to the left.

The construction and mounting of the tools can be considerably varied. In Figure 7 a tool holder block 21a is shown bolted to the underside of the table. This block is recessed to accept the tool proper, indicated at 22, and the tool is held in place by a clamp 23 and bolts 24, and forced against an abutment on the block 21a by a set screw 25.

Yet another modification is shown in Figures 9 to 12 inclusive. Here a pair of blocks 26 are bolted to the outside rails of the bed near one end thereof. The tools are mounted on the table in the position indicated at 27, and near one end of the table. When this is done, those blocks 25 which stop the table if it traverses too far to the left in Figures 9 and 10 may be located intermediate the ends of the table in the position shown at 28.

In this modification the two tools at each side of the table are located close together and may be fastened against the same tool block 29 as shown in Figure 12, the tools being engaged in recesses in the block and being held by clamping means indicated at 30 and 31. One of the tools 32 has its cutting face so directed as to cut into the block 26 at one end of the bed. The other tool 33 is so directed as to cut into the opposite block at 28.

Whether the stopping means for each corner 40 of the table are provided or just one stopping device at either end, where the stopping devices are located or how arranged is a matter of preference, the point being that when the table escapes, a tool at once begins cutting against an emergency cutting block, thereby stopping the table.

Having thus described my invention what I claim as new and desire to secure by Letters Patent is:

50. 1. In a device having a bed and a table driven along said bed, means for stopping the movement of the table should it escape from drive control at the end of its stroke, comprising a cutting tool element and a cutting block element, one of these elements under control of the table and one of them under control of the bed, located so that upon the escape of the table its momentum will be expended in a cutting operation by said tool element upon the cutting block element.

2. In a device having a bed and a table driven along said bed, means for stopping the movement of the table should it escape from drive control at the end of its stroke, said means comprising a cutting tool element and a cutting block element, one of these elements under control of the table and one of them under control of the bed, located so that upon the escape of the table its momentum will be expended in a cutting operation by said tool element upon the cutting block element.

65. 3. In a device having a bed and a table driven along said bed, means for stopping the movement of the table should it escape from drive control at the end of its stroke, said means comprising a cutting tool element and a cutting block element, one of these elements under control of the table and one of them under control of the bed, located so that upon the escape of the table its momentum will be expended in a cutting operation by said tool element upon the cutting block element, the cutting tool element consisting of a plurality of tools, so that the cut will be divided among the said tools.

70. 4. In a device having a bed and a table driven along said bed, means for stopping the move-

ment of the table should it escape from drive control at the end of its stroke, comprising a cutting tool element and a cutting block element, one mounted on the table and one on the bed and arranged to come into operative cutting relationship promptly upon the escape of the table, whereby the table movement will be expended in the operation of forming a cut by said tool element.

4. In a device having a bed and a table driven along said bed, means for stopping the movement of the table should it escape from drive control at the end of its stroke, comprising a cutting tool element and a cutting block element, one mounted on the table and one on the bed and arranged to come into operative cutting relationship promptly upon the escape of the table, whereby the table momentum will be expended in the operation of forming a cut by said tool element, there being a cutting tool element and block element for each of the four corners of the table.

5. In a device having a bed and table driven along said bed, means for stopping the movement of the table should it escape from drive control at the end of its stroke, comprising a cutting tool element and a cutting block element, one mounted on the table and one on the bed and arranged to come into operative cutting relationship promptly upon the escape of the table, whereby the table movement will be stopped in the operation of forming a cut by said tool element, the cutting block element being removably mounted so as to be replaced or turned about after an emergency cutting operation.

6. In a device having a bed and a table driven along said bed, means for stopping the movement of the table should it escape from drive control at the end of its stroke, comprising a cutting tool element and a cutting block element, one mounted on the table and one on the bed

and arranged to come into operative cutting relationship promptly upon the escape of the table, whereby the table movement will be stopped in the operation of forming a cut by said tool element, the cutting tool element comprising a plurality of tools.

7. In a device having a bed and a table driven along said bed, means for stopping the movement of said table should it escape from the drive control at the end of its stroke, comprising a protuberance on the table forming a portion to be cut against and a cutting tool means mounted on said bed and arranged to come into operative cutting relationship with said portion of said table, promptly upon escape of said table, whereby the table movement will be stopped in the operation of forming a cut by said tool means.

8. In a device having a bed and a table driven along said bed, means for stopping the movement of said table should it escape from the drive control at the end of its stroke, comprising a protuberance to be cut against on the bed, and a cutting tool means mounted on said table and arranged to come into operative cutting relationship with said portion of said bed promptly upon escape of said table, whereby the table movement will be stopped in the operation of forming a cut by said tool means.

9. In a device having a bed and a table driven along said bed, means for stopping the movement of said table should it escape from drive control at the end of its stroke, comprising cutting tool means rigidly connected when in use with one of said element, and arranged to come into operative cutting relationship with material to be cut against, rigidly connected when in use with the other of said elements, promptly upon escape of said table, whereby the table movement will be stopped in the operation of forming a cut by said tool means.

JOHN M. WALTER.
